AUTOMATIC CLEAR SIGN PRINTING
MECHANISMHenry L. Pitman, Melbourne, Fla., assignor to
Underwood Corporation, New York, N. Y., a
corporation of Delaware

Application August 20, 1948, Serial No. 45,372

12 Claims. (Cl. 235—60.17)

1

This invention relates to combined typewriting and computing machines and more particularly to machines wherein a single keyboard is employed, such as found on ordinary typewriters.

Machines of the type with which this invention is particularly concerned comprise a computing base surmounted by a typewriter cooperating therewith. Within the base are normally contained a plurality of registers located in lateral alignment across the front thereof. For running amounts into the wheels of the registers, there is provided a set of differential operator bars for each register.

The typewriter carriage is provided with a plurality of column units extending horizontally from the rear thereof, and as the carriage moves into a computing zone corresponding to a column on the work sheet, one of the column units, which may carry a plurality of dogs, depresses a vertically extending plate, thereby selecting one of the registers for operation. If the column unit carries more than one register selecting dog, then, of course, more than one register will be selected for operation.

The differential operator bars which actuate the wheels of the registers are provided with indexing pins which are set in accordance with the depression of numeral keys of the typewriter. When a numeral key is depressed, the digit represented by said key is printed and the digit value is also indexed in one of the differential operator bars. Machines of the character with which this invention is concerned are normally provided with a continuously operating power source and a one-revolution clutch which, when engaged, connects a cycling general operator to the constantly rotating power source. After all of the digits of an amount have been selected, the one-revolution clutch is engaged, thereby cycling the machine and running the selected and indexed amounts into the wheels of the selected register or registers.

With machines of the type with which this invention is concerned, it is possible to automatically print totals. That is to say, after one or more amounts have been entered into a register, the amount then standing in the wheels of the register may be automatically read out and printed. For accomplishing this purpose, a set of total reading feelers is provided for each register and each register wheel is provided with a spiral arrangement of stops. When it is desired to print a total, the set of feelers is released and the individual feelers of the set move forward into engagement with the stops, the amount of for-

2

ward movement being determined by the particular digits standing in the wheels. These different forward positions of the feelers are then employed in selecting the amount to be printed.

5 The machine is also provided with a fugitive-one mechanism, making it capable of recording and printing true overdrifts as well as true positive amounts.

10 When a total is automatically read out of a register and printed, the amount standing in the register is indexed in the differential operator bars for said register, and during the subsequent cycle of the machine, which always follows a total printing operation, the register moves to its 15 subtractive position and the indexed amount is subtracted out of the register thereby leaving the register clear.

15 The general form of the machine, as set forth above, is well known and is more particularly described in my prior Patent No. 2,372,681. Also described and shown in said patent is a mechanism whereby a star or other indicating symbol is automatically printed following a total taking operation if the register is properly cleared. In 20 said patent, a star is only printed when a register is cleared as a result of a total taking operation.

25 It has been found desirable to print a star or other clear sign in certain columns wherein a register is cleared by an operation other than a total taking operation. For example, in certain bookkeeping setups, a Proof column is provided, and when an amount is typed in the usual Old Balance column, said amount is run into at least two registers one of which is a "proof" register.

30 After the operator has entered the appropriate Debits and Credits and the machine has automatically printed the new balance, the carriage is tabulated to the Proof column where the operator again copies the old balance. At this 35 carriage position, the "proof" register is again selected, but this time it is selected subtractively so that during the cycle following the typing of the old balance, the amount is run into the register subtractively thereby clearing the register.

40 After the operator has copied the old balance 45 in the same way in both the Old Balance column and the Proof column. In order that the operator may be made aware of the fact that the old balance has been correctly copied, it is desirable to automatically print a clear sign in the Proof column, and this cannot be accomplished with my prior Patent No. 2,372,681 referred to above.

50 It is, therefore, a primary object of this invention to provide, in a combined typewriting and

computing machine, an improved arrangement whereby a star or other clear sign may be automatically printed in any desired columns of a work sheet without the necessity of taking an automatic total in such columns.

It is a further object of this invention to provide a reliably operable arrangement whereby a clear sign will be printed at only certain definite preselected letter space positions.

It is a still further object of this invention to provide an improved means whereby a clear sign will be printed only when the particular register selected for operation in a certain column is clear.

It is another object of the invention to provide a means for printing a clear sign which is operable early in the second half cycle of a cyclically operating computing machine.

These and other objects, features and advantages of the present invention will become more readily apparent as the description of a preferred embodiment of the invention proceeds.

Referring now to the drawings:

Fig. 1 is a perspective view of a portion of a combined typewriting and computing machine showing the details of the present invention.

Fig. 2 is a side elevation of the general operator mechanism and shows a portion of the means for rocking the registers into their adding or subtracting positions.

Fig. 3 is a view similar to Fig. 2 but shows the relation of the parts after a cycle has progressed to approximately the one fourth point.

Fig. 4 is a view similar to Fig. 2 but shows the relation of the parts at the time a cycle has reached the halfway mark.

Fig. 5 is a side elevation of the tens carry-over mechanism and shows the means for restoring the clear sensing feelers to their normal position.

Fig. 6 is a perspective view showing part of the mechanism for releasing a state control slide for forward movement to an addition or subtraction determinative position.

Fig. 7 is a front elevational view of a portion of the mechanism shown in Fig. 6.

Fig. 8 is a plan view of a modification of one of the features of the invention.

Fig. 9 is a plan view of a further modification of one of the features of the invention, and.

Fig. 10 is a perspective view showing the mechanism whereby various functions of the machine are controlled by the carriage.

Describing first the cycling mechanism and referring primarily to Figs. 2, 3 and 4, it will be observed that the usual general operator bar 10 has been provided. During a cycle of operation of the machine, general operator bar 10 is moved from its Fig. 2 position to the position shown in Fig. 4 and then back to the Fig. 2 position by means consisting in general of a bar 11 to which said general operator bar is operatively connected. The bar 11 is moved toward the front of the machine and back to the Fig. 2 position by means of a crank arm 12 fixed to a shaft 13 and provided with a roller 14 fitting within a groove 15 in a plate 16 secured to said bar through the intermediary of a stiffening member 17. The shaft 13 is connected for one-revolution operation to a continuously rotating power source through the usual one-revolution clutch, as described in my prior Patent No. 2,178,702.

The forward end of bar 11 is provided with rack teeth 18, which are constantly meshed with a pinion 19 rotatable upon a fixed stud 20. Fixed to a cross shaft 21, which corresponds to shaft 65 of Patent No. 2,178,702, mentioned above, is

a gear segment 22 which is meshed with pinion 19. By referring to my above mentioned patent, it will be seen that the other end of shaft 21 carries a gear segment similar to segment 22, which, through a pinion similar to pinion 19, is drivingly connected to a rack bar similar to bar 11 for moving the opposite end of general operator bar 10, thus assuring that the two ends of the general operator bar will move in unison.

As seen in Figs. 2, 3 and 4, a generally V-shaped member 23 is fixed to the cross shaft 21, and upon one arm of said V-shaped member is pivoted at 24 a pawl 25. A spring 26 extends between a pin 27 on a tail portion of said pawl and a pin 28 on the other arm of said V-shaped member and urges said pawl in a clockwise direction, as viewed in Fig. 2, about its pivot 24. Pawl 25 has an extended end portion 29 providing a pair of shoulders 30 and 31 between said end portion and the main body of the pawl for a purpose which will presently appear.

Slidably mounted upon a square stud 32, fixed to the framework, is an arm 33, one end of which is pivotally connected at 34 to an arm 35 fixed to a cross shaft 36. Cross shaft 36 is similar to shaft 148 of my prior Patent No. 2,192,365 and serves when rocked to move a selected register or registers from a normally neutral to an adding or subtracting position, as fully explained in said patent. Shaft 36 is rocked from its Fig. 2 position to its Fig. 3 position by rearward movement of the arm 33, and for moving said arm the following mechanism is provided.

A cam plate 37 having a cam slot 38 is pivotally mounted upon a shaft fixed in the frame of the machine and is held upon said shaft by means of a screw 39. A pair of push pins 40 and 41 are mounted in the cam plate 37, the push pin 40 co-operating with shoulder 30 of the pawl 25 and the pin 41 cooperating with shoulder 31 of said pawl. A cam follower 42 is fixed to the arm 33 and rides in the cam slot 38.

As previously pointed out, the bar 11 is moved toward the front of the machine, that is to say from the Fig. 2 position to the Fig. 4 position during the first half of the cycle. As will readily be understood, the forward movement of bar 11 will result in counterclockwise rotation of segment 22 and V-shaped member 23. During approximately the first quarter of the cycle, the pawl 25 will be held up in the position shown in Figs. 2 and 3 so that extension 29 and shoulder 30 thereon will be resiliently held in engagement with push pin 40 by the spring 26. As the V-shaped member 23 begins its counterclockwise movement, the shoulder 30 on pawl 25 will push the pin 40 from the Fig. 2 position to the Fig. 3 position thereby rotating the cam plate 37 counterclockwise about its axis. Since the follower 42 on arm 33 stays in the cam slot 38, counterclockwise rotation of cam plate 37 from its Fig. 2 position will result in a rearward movement of arm 33 to the Fig. 3 position, as will readily be understood.

As the arm 33 moves rearwardly, the previously selected registers will be moved into an adding or subtracting position by the resultant rotation of shaft 36, as explained in my prior Patent No. 2,192,365, referred to above. The registers are, of course, moved to their operative positions before the general operator bar 10 has moved far enough to pick up any of the usual differential operator bars.

As the cycle progresses from the Fig. 3 position to the Fig. 4 position, the pawl 25 is moved by the V-shaped member out of engagement with push

pin 40 and into engagement with push pin 41 and held resiliently engaged therewith by spring 28, as shown in Fig. 4.

During the second half of the cycle, the crank arm 12, by continuing its clockwise rotation, draws the rack bar 11 toward the rear of the machine to return the parts from the position shown in Fig. 4 to their normal position shown in Fig. 2. This rearward movement of bar 11 will, of course, result in clockwise rotation of gear segment 22 and V-shaped member 23. As V-shaped member 23 rotates clockwise, the shoulder 31 on pawl 25 pushes against pin 41 on the cam plate 37 thereby rotating said cam plate in a clockwise direction and causing the cam follower 42 and consequently the arm 33 to move toward the front of the machine. Forward movement of arm 33 causes counterclockwise rotation of shaft 36 and consequently rocks whichever register or registers have been moved to an adding or subtracting position during the first part of the cycle back to a neutral position, as explained in my prior Patent No. 2,192,365, referred to above.

For resiliently holding the cam plate 37 in its two operated positions, a detent is provided. Said detent may conveniently consist of a member 43 provided with notches 44 and constrained to rotate with said cam plate and having in cooperation therewith a pawl 45 pivotally mounted at 46 upon a stationary part of the machine and carrying a roller 47 which is urged by a spring 48 into engagement with member 43.

As explained in my Patent No. 2,192,365, referred to above, a mere cycling of the machine will not result in the rocking of a register into its adding or subtracting position. In order that a register may be moved into an operative position during a cycle, it is necessary first to select one or more registers. In the type of machine with which the present invention is particularly concerned, register selection is predetermined and is accomplished by the carriage of the machine depressing one or more register selecting cam plates. Depression of a register selecting cam plate causes, among other things, the withdrawal of an "add" latch 49 (see particularly Fig. 1) from a notch in a state control slide 50, thereby allowing said slide to be moved toward the front of the machine by a spring 51 until its forward movement is arrested by a second or "subtract" latch 52.

The state control slide is provided at its front end with a cam slot 53 into which slot extends a follower fixed to a slidable bail. As explained in my prior Patent No. 2,192,365, forward movement of state control slide 50 to the point where it is arrested by the "subtract" latch 52 serves to position the slidable bail at a location wherein subsequent clockwise rotation of shaft 36 will rock the register, controlled by the selected state control slide, into its adding position.

Since the particular construction of the slidable bail and its connection with the register are not within the confines of this invention, the same have not been illustrated in the drawing and reference is to be had to my Patent No. 2,192,365 for the details thereof.

As likewise explained in my Patent No. 2,192,365, the depression of a second cam plate by the carriage will withdraw the "subtract" latch 52 and allow state control slide 50 to move forward to its fullest extent, provided the "add" latch 49 has first been withdrawn, to thereby position the above mentioned slidable bail in a location such

that subsequent clockwise rotation of shaft 36 will rock the register into its subtraction position.

In my prior Patent No. 2,160,487, an arrangement is described whereby a single register may be made to perform the function of two registers by the expedient of operatively connecting only half of the differential operator bars at a time for that register to the usual denominational jacks which are depressed seriatim by the carriage during its travel across a column. In the machine constructed in accordance with the present invention, a good part of the register selecting mechanism has been preserved and while, as described below, the machine in its present form is not provided with mechanism enabling one register to serve as two registers, it lends itself to comparatively simple change-over to a split register machine if such is desired.

Referring now to Figs. 6 and 7, it will be seen that the machine of the present invention is provided with a pair of coupler section shifters 54 and 55 similar to coupler section shifters 111 of my above mentioned Patent No. 2,160,487. Each of the coupler section shifters is guided for vertical sliding movement by a plurality of guide studs 56 fixed in a stationary register bar guiding plate 57. When the coupler section shifters are raised from the Fig. 6 position to the Fig. 7 position, the couplers 58, only partially shown in Fig. 7, are raised to a position to operatively connect the differential operator bars with the above mentioned denominational jacks, as will readily be understood.

The coupler section shifters 54 and 55 are operated by the depression by the carriage of a cam plate 300. As may readily be seen in Fig. 10, there is a cam plate 300 corresponding to each of the registers of the machine; in the present instance three have been shown. The rearmost cam plate 300 rests upon a tab 301 of an intermediate plate 302. Through a push rod 303, the plate 302 is operatively connected to one end of a lever 59 pivotally mounted upon a shaft 59'. It is to be understood that there is an intermediate plate 302, a push rod 303 and a lever 59 corresponding to each of the other register selecting cam plates 300, but that for clearness of illustration, they have not been shown.

Operation of lever 59 causes rotation of a lever 60, Fig. 6, pivotally mounted upon a part of the framework 61 of the machine by a stud shaft 62. There is a pin-and-slot connection 63 between one end of lever 60 and an arm 64 fixed to one end of a rock shaft 65 mounted in a pair of ears 66 of the framework 61, so that rotation of lever 60 causes shaft 64 to be rocked clockwise, as viewed in Figs. 6 and 7. An arm 67 is fixed to the opposite end of rock shaft 65 and carries a stud 68 which extends into an opening 69 in the coupler section shifter 54. It will, therefore, be understood that when the end of lever 59 is raised from the position shown in Fig. 6, such movement will result in raising the coupler section shifter 54.

Since it is not desired to use the register controlled by a single state control means 50 as two registers, it is necessary to raise the coupler section shifter 55 at the same time that shifter 54 is raised, and for that purpose, the following mechanism is provided.

An intermediate lever 70, having one end 71 overlying the stud 68, is pivotally mounted upon the guide plate 57 by means of a stud 72. The opposite end of lever 70 overlies one end of a lever 73, which lever is also pivotally mounted upon the guide plate 57 by a stud 74. The lever 73 is simi-

lar to latch rod retracting lever 256 of my Patent No. 2,160,487, but unlike said lever 256, the lever 73 is provided with a stud 75 extending into an opening 76 in the coupler section shifter 55 so that when the shifter 54 is raised by the stud 68, the levers 70 and 73 are rocked in such manner as to cause the stud 75 on lever 73 to raise the shifter 55, as will readily be understood. Lever 73 is normally held in its inactive position by a spring 73'.

As in the construction explained in my Patent No. 2,160,487, the "add" latch 49 is provided with a notch 77 fitted against the edges of lever 73. Thus it will be understood that the depression of a particular cam plate 300 by the carriage of the machine will serve to completely condition a given register for addition, inasmuch as the depression of the cam plate will allow the state control slide to move forward to its "add" position and will also operatively connect all of the differential actuators for said register with the universal set of denominational jacks. The upper ends of the denominational jacks are indicated generally at 304 in Fig. 10.

In the machine in which the present invention has been embodied, the "subtract" latches 52 are all withdrawn from engagement with their respective state control slides 50 at the same time. Each "subtract" latch 52 is pivotally connected as at 78, Fig. 6, to an arm 79 fixed to a universal cross shaft 80. When the cross shaft 80 is rocked counterclockwise from its Fig. 6 position, all of the "subtract" latches 52 are raised.

For a description of a preferred means of operating the shaft 80, reference is to be had to Fig. 10. A subtraction determining cam plate 305 is operatively connected through an intermediate plate 306 and a push rod 307 to one end of an L-shaped lever 308. The L-shaped lever 308 is mounted upon a rock shaft 309 and is connected by a bail 310 to one end of a lever 311 also mounted upon the shaft 309. The lever 311 is urged in a clockwise direction, as viewed in Fig. 10, by a spring 312 and is pivotally connected by a pin 313 to one end of a link 314. The opposite end of link 314 is pivotally connected to one end of a lever 315 mounted upon a rock shaft 316. The opposite end of lever 315 is connected by a bail 317 to one end of a latch member 318 also mounted upon the shaft 316.

The spring 312 serves to hold the cam plate 305 in an elevated position and also serves to position a tongue 319 of the latch member 318 underneath one arm of a generally T-shaped member 320. The member 320 is pivotally connected at 321 to a stationary part of the machine and is urged by a spring 322 in a clockwise direction, as viewed in Fig. 10. One arm of the member 320 is pivotally connected by a pin 321 to a link 322'. The link 322' is provided with a slot 323 into which is fitted a pin 324 mounted upon an arm 325 fixed to the aforementioned shaft 80. A spring 326 connects the pin 324 to an offset portion 327 of the link 322'.

If a register is to be selected for subtraction in a particular column, a column unit 144 which will control the operation of the machine in that column is provided with a tappet 328 for depressing one of the cams 300 to select the register for addition and to raise the couplers 58, as previously described, and is also provided with a tappet 329 for depressing the subtraction cam plate 305. Through the linkage system above described, depression of cam plate 305 serves to withdraw the tongue 319 from beneath the arm

of T-shaped member 320, whereupon the spring 322 rocks the member 320 clockwise until said member abuts a stationary pin 330. When the member 320 is in abutment with the pin 330, the arm of said member lies in front of the tongue 319 so that even though the tappet 329 should leave the cam plate 305, said plate will not at that time move upward because the tongue 319 cannot move to the right as viewed in Fig. 10.

10 When the member 320 is rocked clockwise, the link 322' pulls the pin 324 on arm 325 toward the rear of the machine to thereby rock the cross shaft 80 in a counterclockwise direction as viewed in Fig. 10 and thereby withdraw all of the "subtract" latches 52, as previously explained.

15 If a register is to be selectable in a given column alternately for ordinary computing and for automatic total-taking, the column unit will be provided with two tappets 328 and two tappets 329. One of the tappets 328 and 329 will cooperate with the cam plates 300 and 305 when said cam plates are in their forward, or ordinary computing, positions and one of the tappets 328 and 329 will cooperate with the cam plates 300 and 305 when said cam plates are in their rearward, or automatic total-taking, positions. It is well known that in machines of the type with which this invention is particularly concerned, the cam plates which control the functioning of the machine may be rocked from a non-total-taking position to a total-taking position, and one manner of rocking such plates is explained in my prior Patent No. 2,372,681.

20 One arm of the T-shaped member 320 is provided with a cam portion 331 and a dwell 332 for cooperating with a pin 333 carried by a bar 334. The bar 334 is part of the means for moving the general operator bar 10 and early in the cycle the pin 333 contacts the cam portion 331 to thereby rock the member 320 in a counterclockwise direction. As the member 320 moves counterclockwise, the offset portion 327 of link 322', through the spring 326, pulls upon the arm 325 to attempt to rock the cross shaft 80 in a clockwise direction. If a register has been selected for subtraction the shaft 80 cannot at this time move clockwise because the end of the "subtract" latch will be resting upon the state control slide. Spring 326 will, therefore, yield until later in the cycle when the state control slide has been returned to its normal position, in a manner to be later described, whereupon the spring 326 will snap the "subtract" latches down into their respective notches in the state control slides.

25 The column units 144 are adjustably mounted upon the carriage, partially indicated at 335, and may be placed in any desired positions in accordance with the work-sheet columns.

30 Referring now to Figs. 1 and 5, a portion of the base of a combined typewriting and computing machine, of the type to which the present invention is particularly adapted, is shown. Since the present machine has three single registers, or three interspersed registers, as disclosed in my recently issued Patent No. 2,436,055, three fore-and-aft movable state control slides 50 are at least partially shown. Since the operation of all of the registers and all of the state control slides is identical, only one state control slide has been shown in its entirety.

35 Extending parallel to the state control slide 50 for each register is a fore-and-aft movable slide 81. Each slide 81 is provided with an elongated slot 82 at its forward end and is mounted 40 for guided movement upon a pin 83 fixed to the

framework of the machine. Each slide has an elongated slot 84 in its rear end guidably slideable upon a headed stud 85 fixed in a state control restorer bar 86, the operation of which will be presently described. Each slide 81 is constantly urged toward the rear of the machine by a spring 87. In its forward end, each of the slides 81 is provided with a slot 88 for receiving one arm of a bell crank 89 stationarily pivoted at 90 to the machine framework. To the other arm of each bell crank 89 is articulated, by a pin-and-slot connection 91, a sensing bar generally indicated at 92. One leg 93 of sensing bar 92 extends through an opening 94 (see Fig. 5) in the framework of the machine, and another leg 95 thereof is guided in a groove 96 cut into the machine framework. At its upper end, each sensing bar is provided with a guide member 97 riding within a slot 98 in a stationary member 99 and with a sensing spur 100 for a purpose to be presently described. Each of the sensing bars 92 is urged to its inactive position by a relatively light spring 92', as shown in Fig. 5.

A register clearance detecting bail bar 101 has side arms 102, which are pivotally mounted upon side plates 103 of a register frame. Only one of the side plates 103 is shown in Fig. 5, and inasmuch as the plates 103 correspond to plates 101 of my Patent No. 2,436,055 and the registers to be used in the present machine may be identical with the registers described in detail in said patent, reference is to be had thereto for the details thereof. The particular machine chosen for illustration is of the interspersed register type, as disclosed in my said patent and for that reason, the bar 101 is illustrated in Fig. 1 as having a row of cam-bevel-sided teeth 104 and interdental notches 105. As described in said patent, a register consists of a plurality of wheels 106 for each denominational order, and a detent arm 107 is provided for each wheel. Each wheel is provided with a pair of crescents 108 cut into adjacent teeth. When the wheel is in the rotative position corresponding to "0," the crescents 108 are aligned with a tail portion of detent arm 107. A spring 109 urges each arm 107 toward its wheel. It will, therefore, be apparent that when the crescents are aligned with the tail portion of said arm, the arm will not stand out as far as when the wheel is in a position other than "0" and the crescents are not so aligned. The purpose of the interdental notches is to allow the detent arms 107, corresponding to the wheels of a non-selected register of the interspersed group, to be positioned outwardly by wheels of that group which are not in a "0" position without affecting the bail bar 101, all as described in my Patent No. 2,436,055, referred to above.

Bail bar 101 is urged by a spring 110 toward the arms 107 and when a register is clear, that is to say when all the wheels of the register are standing at "0," bar 101 is so positioned as to be out of the path of downward movement of spur 100 of feeler member 92, as may be seen in Fig. 5. When any one or more wheels of a register are standing at a position other than "0," arms 107 corresponding to such wheels are moved outwardly thereby moving the bail bar 101 outwardly and into the path of, and preventing downward movement of, spur 100, as shown in Fig. 1.

Thus it will be seen that the spring-urged fore-and-aft movable slide 81, together with the sensing bar 92 and its sensing spur 100, constitutes

a sensing means for ascertaining whether a register is clear or whether there is an amount standing in the wheels of said register.

While above, reference is made to a "selected register" for purposes of explaining the presence of the interdental notches 105 in the bail bar 101, for the remainder of the specification it is to be understood that when reference is made to a "selected register," the term is intended to include a single register of a multiple single-register machine, as well as one register of an interspersed group.

Each of the slides 81 is provided with a notch 111 in the side thereof, and extending into each notch 111 is an arm 112 fixed to a cross shaft 113. Also fixed to said cross shaft is an arm 114 pivotally connected at 115 to a vertically movable member 116 guided in a stationary cross piece 117, as seen in Fig. 5.

The upper end of member 116 abuts a flange 118 on one end of a lever 119 pivotally mounted upon a stationary shaft 120. The lever 119 is urged by a spring 121 in a clockwise direction, as viewed in Fig. 1, about the shaft 120, and at the end opposite the flange 118 is provided with a flange 122 overlying one end of a draw link 123. The draw link 123 is urged to inoperative position by a spring 124 and is provided at one end with a toothed pawl 125 for engagement with the usual snatch roll 126. Intermediate its length, the draw link 123 is pivotally connected to one end of a stationarily fulcrumed lever 127 to the opposite end of which is operatively connected by a link 128, a type bar 129 carrying a star or other clear sign 130.

When any one of the slides 81 is moved by its spring 87 toward the rear of the machine, the forward edge of the notch 111 will pull the arm 112 toward the rear thereby rocking cross shaft 113 and causing the vertically movable member 116 to be raised. This raising of member 116 will, of course, rock the lever 119 and thereby cause the pawl 125 on draw link 123 to be moved into engagement with the snatch roll 126. As the draw link 123 is moved by the snatch roll, the type bar 129 will be moved into engagement with the work sheet carried by the platen of the type-writer unit, as is well known.

While that part of the star printing train from the lever 119 to the type bar 129 is shown in Fig. 1 as being located to the left of the vertically movable member 116, it has been so shown only for the sake of clearness of illustration, and in the actual construction of the machine, it is located to the right of member 16.

When work is being performed, which in a machine with which this invention is primarily concerned may be either a manual item entry or an automatic total in a column on a work sheet, it is essential that a star or other clear sign be printed only if the particular register in which the work is being performed in that column becomes clear. In other words, unless the particular register selected to be moved to its adding or subtracting position from its normally neutral position is cleared during the cycle which follows the printing operation, a star should not be printed.

To insure that clear sign printing is controlled by the particular register selected for operation in a given column, an interlock has been provided between the state control means for each register and the clear condition sensing means for that register which will prevent the operation of

the sensing means at all times when the state control slide has not moved forward.

In Fig. 1 is shown a member 131 pivotally mounted upon the pin 83, which, as previously pointed out, also serves to guide the forward end of slide 81. A pin-and-slot connection 132 serves to operatively connect each of the members 131 to its state control slide, and each member 131 is provided with a hook 133 extending into the path of movement of a pin 134 mounted in each of the sensing slides 81. Until a state control slide 50 has been moved forward to determine an adding or subtracting condition of its register, the hook 133 will prevent rearward movement of the associated sensing slide 81 and, therefore, prevent operation of the clear sign printing train. When a state control slide 50 moves forward, the member 131 associated therewith will be caused to swivel about the pin 83 due to the pin-and-slot connection 132, and this swiveling of member 131 will cause the hook 133 thereon to move out of the path of movement of the pin 134, as will readily be appreciated.

In some instances, it is desirable to prevent the printing of a clear sign at all times except when a register has been selected for "subtraction," and for accomplishing that result, the arrangement shown in Fig. 8 is contemplated. Attached by a screw 135, or otherwise, to the member 131 is a member 136 having an upturned lip 137 for bearing against one edge of the member 131 and having an elongated tail 138 for extending beyond the end of hook 133.

If the "add" latch 49 is withdrawn and the state control slide 50 consequently moved forward, in the direction of its arrow in Fig. 8, to the position wherein its register will be rocked to its adding position during the cycle, as previously explained, the hook 133 of member 131 will be withdrawn from the path of movement of pin 134, but the elongated tail 138 of member 136 will not be moved far enough to be out of the path of pin 134. Consequently, the sensing means cannot operate when a register has been selected for addition. If, however, the "subtract" latch 52 is now withdrawn to allow the slide 50 to continue its forward movement, such additional forward movement will cause the member 131 and member 136 attached thereto to be rotated about the pivot point 83 to a position wherein the elongated tail portion 138 is out of the path of movement of pin 134, and the sensing slide 81 will consequently be able to move toward the rear of the machine, indicated in Fig. 8 by the arrow on member 81.

Should it be desirable to prevent printing of a clear sign at all times except when a register is selected for "addition," it is contemplated to employ the arrangement shown in Fig. 9, wherein the member 136 of Fig. 8 is replaced by a member 139. The member 139 is fastened to the member 131 by a screw 140, or otherwise, and is provided with a lip 141, similar to the lip 137 of member 136, for bearing against the side of the member 131. Member 139 is provided with a tail portion 142, which is longer and wider than the tail portion 138 of member 136 and is cut away at 143 to provide a space between the hook 133 and the end of tail portion 142 into which the pin 134 on slide 81 may move. If with the construction shown in Fig. 9, the "add" latch 49 is withdrawn to allow the state control slide 50 to move in the direction of its arrow in Fig. 9 to the position wherein the register is selected for "addition," the member 131 and the member

139 connected thereto will be rotated about the pivot 83 to a position wherein the hook 133 is out of the path of movement of the pin 134, but the end of tail portion 142 will not have moved to a point of alignment with said pin. The sensing slide 81 will, therefore, be free to move to the rear, the direction shown by its arrow in Fig. 9, and consequently institute the printing of a clear sign, as previously explained.

10 In the Fig. 9 construction, if both the "add" and "subtract" latches are withdrawn from the state control slide, said slide will move all the way forward and thereby rotate members 131 and 139 to a point where the end of tail portion 142 will block rearward movement of slide 81. It will later become apparent that there is no possibility of the slide 81 moving to the rear during the time required for the state control slide 50 to move to its "subtract" position. That 15 is to say, whenever a register is selected for subtraction, the opening formed between the hook 133 and the end of tail portion 142 by the cutaway 143 is momentarily exposed to the pin 134, but the slide 81 is prevented from movement at 20 that time by other means.

When a clear sign is to be printed in a column on a work sheet, it is desirable that said sign be printed at only one particular letter space position of the carriage and said letter space 25 may appropriately be the one immediately following the lowest denomination of the column of numbers.

Column unit 144, in addition to the tappets 328 and 329 previously referred to, is provided 30 with a tappet 336 for depressing seriatim the aforementioned denominational jacks 304. As described in my prior Patent No. 2,323,622, as the carriage escapes from the position wherein the tappet 336 is resting upon the jack 304 corresponding to the lowest denominational order, a cycle instituting tooth 337 on the column unit 144 passes over a cycle trip lever partially indicated at 338 in Fig. 10. Depression of the cycle trip lever 338 causes the machine to cycle, as 40 explained in my said Patent No. 2,328,522.

After the tooth 337 passes over the cycle trip lever 338, the carriage comes to rest in the letter space position immediately following the lowest order letter space position, and it is in this letter space position that it is desirable to print the clear sign. For enabling the slides 81 to move rearward to thereby institute clear sign printing, the column unit 144 is provided with a tappet, or dog, 145 for cooperating with a tooth 146 on a plate 147. The dog 145 is so shaped and positioned as to rest upon the tooth 146 only when the carriage is in the letter space position immediately following the lowest denomination.

Referring now particularly to Fig. 1, it will be seen that the tooth 146 is a part of a member 148 carrying a headed stud 149 mounted within a slot 150 in the plate 147 and a headed stud 151 mounted within a slot 152.

Member 148 is urged upward to the position shown in Fig. 1 by a spring 153 extending between the headed stud 151 and a hole 154 in the plate 147. The plate 147 and its tooth carrying member 148 are constructed as more particularly explained in my prior Patent No. 2,372,681, and by referring to said patent, it will readily be understood that when the tooth 146 is depressed by a pressure applied from the right, the plate 147 will be depressed, but when the tooth is struck from the left, the member 148 is merely depressed

with the headed studs 149 and 151 riding down in their respective slots without depressing the plate 147. The purpose of using such a plate is so that the plate 147 will not be depressed during carriage return operations.

When the plate 147 is depressed, it in turn depresses a plate 155, which through a push rod 156 rocks a crank arm 157 fixed to a shaft 158.

The shaft 158 carries three rods 159 which are normally held in alignment with the sensing slides 81, as shown in Fig. 1, by a helical spring 160 acting upon the shaft 158. Therefore, it will be obvious that the sensing means comprising the slides 81 can operate at only one columnar letter space position, since at only one letter space position in a column is the shaft 158 rotated by the depression of plate 147 to remove the rods 159 from alignment with said slides.

A dog 145 for depressing plate 147 may, of course, be placed upon any column units which control columns in which it is desired to print a clear sign.

If desired, the plate 147 may be made to rock to the rear whenever a total is taken in a manner similar to that described in respect to plate 455 of my hereinbefore mentioned Patent No. 2,372,681, so that a clear sign may be printed in any column whenever a total is automatically taken in said column but not printed when an item is merely entered in said column. If the plate 147 is made rockable during automatic total-taking operations, a dog 145 is provided upon each column unit 144 in a position to be in operative alignment with the tooth 146 when plate 147 is in its "total" position. In any column, for example a proof column, wherein it is desired to print a clear sign at times when a total is not automatically taken, the dog 145 will, of course, be so positioned as to be in operative alignment with the tooth 146 when plate 147 is in its unrocked or non-total-taking position.

In addition to the clear sign printing being confined to one particular columnar letter space position and being dependent for its operation upon register selection, it is necessary that said printing be delayed until after the cycle has progressed to a point where the register wheels have been completely turned. Not until after the differential operator bars have completed their forward movement and the tens carry-over has had time to operate is it possible to ascertain whether the computation has resulted in a clear register. For the purpose of delaying operation of the clear sign printing train until the second half of the cycle, the following mechanism is employed.

A crossbar 161, the operation of which will later be more fully explained, is normally positioned as shown in Figs. 1, 2 and 5. Each of the sensing slides 81 is provided with a post 162, which is in abutting relation to the crossbar 161 when the machine is in its normal condition, that is, when a cycle is not in progress. When a cycle has progressed to approximately the one quarter point, the crossbar 161 begins to move toward the rear of the machine so that by the time the cycle has progressed to the halfway mark, the crossbar 161 has moved to the position shown in Fig. 4, wherein it no longer interferes with free rearward movement of the slides 81.

Fixed to the cross shaft 36, which, as previously explained, is rocked clockwise, as viewed in Figs. 1 to 4, at the beginning of a cycle, is an arm 163 to which is pivotally connected at 164 a link 165 having a slot 166 in one end thereof. To the cross shaft 113, which, as previously explained,

must be rocked counterclockwise, as viewed in Figs. 1 to 4, to institute operation of the clear sign printing train, is fixed an L-shaped arm 167 provided with a pin 168 extending into the slot 166. Arm 167 is also provided with a pin 169 between which and a stop pin 170 on the framework of the machine extends a light tension spring 171 for resiliently holding said arm against said stop pin and consequently holding the cross shaft 113 in its neutral position.

The general operator mechanism is so timed as to cause the cross shaft 36 to complete its clockwise rocking movement before the crossbar 161 begins its rearward movement. Therefore, the link 165 is moved forward to the position shown in Fig. 3 wherein the pin 168 on arm 167 is positioned in the back of slot 166 before the crossbar 161 has started to move away from posts 162. Thus while the crossbar 161 serves to lock the clear condition sensing slides 81 before the cycle begins, it will be apparent that this function is taken over by the link 165 and its pin-and-slot connection with the L-shaped arm 167 as the cycle gets under way.

Early in the second half cycle, the cross shaft 36 is rocked counterclockwise of its Fig. 4 position to return the selected register to its normal position, and shaft 113 would at that time be free to be rocked were it not for the following arrangement.

Fixed to the cross shaft 113 near the end opposite the L-shaped arm 167 is an arm 172 carrying a roller 173 on the free end thereof. Secured to the general operator bar 10 by means of a screw 174, or otherwise, is a member 175. As the general operator bar 10 advances to the half cycle position, the member 175 moves over the roller 173 on arm 172, as shown in Fig. 4, to thereby prevent the cross shaft 113 from being rocked. As will readily be appreciated, the member 175 will remain in engagement with the roller 173 until the second half of the cycle has progressed far enough for the register to be returned to its neutral position wherein the bail bar 101 will be in a position to block downward movement of the sensing bar 92 if the register is not clear, as previously explained.

Thus it will be seen that means has been provided for delaying operation of the clear sign printing train until the second half of a cycle has gotten under way. By varying the length of the member 175 or the arm 172, clear sign printing may be instituted at any time during the second half cycle that is found desirable.

After a register has been selected for addition or subtraction by forward movement of its state control slide 50, it is necessary to return the state control slide to its neutral position during the cycle following the computation, and, for this purpose, the hereinbefore mentioned bar 86 is employed. Attached to the bar 86 is an arm 176 pivotally connected at 177 to an arm 178 fixed to a shaft 179. Also fixed to the shaft 179 is an arm 180 pivotally connected at 181 to a hook link 182. Hook link 182 is cooperative with the general operator bar 10 in a manner fully described in my copending application No. 2,654, filed January 16, 1948, it being sufficient here to mention that the hook link 182 is provided with a step 183. As the general operator bar 10 moves forward, the hook link 182 is lifted so that during the return stroke of said general operator bar, step 183 is caught by said bar, and the hook link 182 is thereby drawn toward the rear of the machine. Rearward movement of the hook link

70 182 causes the bar 86 to move rearward, thereby returning the state control slide 50 to its neutral position. Step 183 is also effective to hold the hook link 182 in its rearward position during the forward movement of the general operator bar 10.

192, will, of course, result in rearward movement of the bar 86, as will readily be appreciated. Each of the state control slides 50 is provided with a pin 184 extending into the path of movement of the bar 86, so that as said bar moves toward the rear of the machine, any slide 50 which has been allowed to move forward will be picked up by the bar 86 striking the pin 184 thereon and returned to its normal position. At the very end of the cycle, the step 183 is kicked down out of engagement with the general operator bar 10, and a spring 185 attached to the bar 86 returns said bar and the hook link 192 to the position shown in Fig. 1, as described in my copending application No. 2,654, referred to above.

After any sensing slide 51 has moved rearward to institute action of the clear sign printing train during a cycle, as previously described, it is necessary that said slide be returned to its normal position in order that it may be ready to perform its sensing function during the next computing operation. Since the particular means employed herein for that purpose is a part of the usual tens-transfer and fugitive-one mechanism, said tens-transfer and fugitive-one mechanism will be briefly described, but for a full description of the operation thereof reference is to be had to my prior Patent No. 2,192,365.

Referring now to Fig. 5, one of the differential operator bars is indicated at 186. Said bar carries a plurality of index pins 187 and has rack teeth 188 located upon the forward end thereof. By referring to my Patent No. 2,192,365, mentioned above, it will readily be apparent that there is a differential operator bar 186 for each denominational order of a register. The rack teeth on each of the bars 186 are in constant mesh with the teeth of an idler pinion 189.

The register wheels 106 are rocked rearward into engagement with the idler pinions 189 for subtractive operation and are rocked downward into direct engagement with the rack teeth 188 for additive operation.

A lever 190 corresponding to each of the differential operator bars 186 is pivotally mounted upon a bracket 191 fixed to the general operator bar 10. As is well known, the index pins 187 are set in accordance with the operation of the numeral types of the typewriter unit, the "0" pin being set, as shown, when none of the other pins has been set. As the general operator bar 10 is moved forward during a cycle, the differential operator bars 186 are picked up by the contact of lever 190 and whichever of the index pins 187 has been set, and moved forward to rotate the register wheels 106 by an amount corresponding to the set index pin. On its return stroke, the general operator bar 10 picks up an abutment 192 on each of the differential operator bars to return same to their normal position. The bars 186 are actually moved the last increment of movement to their home position by a spring 193 engaging with a notch in said bars.

If a register wheel is rotated through the transfer point, that is, from "9" to "0" or from "0" to "9," a carry-over trip lever 194 is moved outwardly of the position shown in Fig. 5 to rock a bell crank 195 one end of which is in engagement with a carry-over bar 196. Each carry-over bar 196 is pivotally connected to a stationaryly pivoted lever 197 carrying a roller 198 on one end thereof. The roller 198 on the lever 197 is in lateral alignment with the lever 190 of the next highest denominational wheel for a purpose presently to become apparent.

A spring 199 urges the carry-over bar 196 forward and downward, forward movement being normally prevented by contact of the lever 197 with a stationary shaft 200 and downward movement being arrested by contact between the forward end of bar 196 and a guide comb 201.

Before the carry-over bars 196 can be effectively operated, it is necessary that they be drawn a short distance toward the rear of the machine so that the levers 197 are no longer in contact with the stationary shaft 200, and for this purpose, a crossbar 202 is provided for cooperative engagement with a shoulder 203 on said carry-over bars. The crossbar 202 is connected to move with the crossbar 161, previously described, by means of brackets 204, only one of which is shown.

Crossbar 161 is connected at its opposite ends between a pair of slides 205, only one of which is shown. The slides 205 are each provided with a pair of cam followers 206 for cooperating with a cam 207 fixed to the cross shaft 21, previously referred to.

During the first half of the cycle, the cam 207 is rotated counterclockwise, as viewed in Fig. 5, to draw the crossbar 161 and consequently the crossbar 202 toward the rear. As the crossbar 202 moves rearward, it contacts the shoulders 203 of carry-over bars 196 and thereby moves said carry-over bars rearward to position a flange 208 on one end thereof in abutment with the set "0" index pin 187 of the next highest denominational operator bar 186. If the "0" pin is not set, the flange 208 is positioned in what would be abutting relation with the "0" pin if same were set. If, at this time, a register wheel passes through the transfer point, the bell crank 195 corresponding to said wheel will be rocked to lift the shoulder 203 on the corresponding carry-over bar out of contact with the crossbar 202. Spring 199 will then be effective to draw the carry-over bar 196 forward until the lever 197 contacts the stationary shaft 200. At that time the roller 198 on lever 197 will be positioned far enough toward the rear of the machine to intercept the forward movement of the lower end of lever 190 and thereby cause said lever to pivot about its connection with the bracket 191. The pivotal movement of lever 190 will be just sufficient to cause the upper end thereof to move the differential operator bar 186 forward by an amount equal to one digital distance and position the set index pin in contact with the flange 208 of carry-over bar 196. The additional forward movement of the differential operator bar will cause the register wheel associated therewith to be turned by an amount equal to one digit, as will readily be understood.

A lever 209, shown in Fig. 5, operates the carry-over bar 196 for the lowest denominational wheel and is connected by a bail 210 to the bell crank 195 which is operated by the highest denominational wheel, thus providing a fugitive-one mechanism, as will be understood and as more fully explained in my copending application, Serial No. 2,654, filed January 16, 1948.

During the second half of the cycle, the cross shaft 21 is rotated clockwise, as viewed in Fig. 5, as previously explained. The resultant clockwise rotation of cams 207, by cooperation with the cam followers 206, will cause the slides 205 and the crossbar 202 associated therewith to move forward until the crossbar 202 clears the shoulders 203 on carry-over bars 196, whereupon the

springs 199 will pull said carry-over bar down to the position shown in Fig. 5.

As the crossbar 161 moves forward, it carries forward to its normal position any sensing slide 84, which has moved rearward, by cooperation with the post 162 thereon. Thus it will be seen that the usual tens-carry-over restorer bar 161 is utilized as a primary lock to prevent operation of the clear condition sensing means and has also been made to serve as a restoring means for said sensing means.

From the foregoing description, it will be apparent that an arrangement has been provided, in a combined typewriting and accounting machine, whereby a star or other clear sign may be printed in any desired column of a work sheet when an operation in that column has resulted in clearing the register which has been selected for operation at that columnar position. It is to be particularly noted that in accordance with the present invention, it is of no consequence whether the register is cleared as a result of an automatic total taking operation or as a result of an item entry. It is also to be noted that with an arrangement such as herein disclosed, the star or other clear sign will only be printed at definite preselected columnar letter space positions.

It is also to be noted that clear sign printing and register selection are both under control of the carriage. It is, therefore, possible to check back over a work sheet and determine the place where any error may have occurred. For example, if a clear sign does not appear in a column wherein an automatic total was taken, it will be evident that an error occurred at the time of the automatic total taking operation and the particular register wherein the error occurred may be identified, since at that columnar position it will be known that a certain register was in operation.

Having thus described my invention, I claim:

1. In a computing machine adapted for printing amounts in a column on a work sheet and having a letter spacing carriage, a unit on said carriage for controlling various functions of the machine, a register comprising a plurality of axially aligned wheels, and a cycling general operator for running indexed amounts into the wheels of the register; the improvement comprising spring-operated sensing means for ascertaining the clear condition of the register, a pair of normally effective locks each of which is capable of preventing operation of said sensing means, means for releasing one of said locks at a predetermined columnar letter space position of the carriage, means for releasing the other of said locks during a machine cycle, and a clear sign printing train operable only when both of said locks are released and when the sensing means finds the register to be clear.

2. In a computing machine adapted for printing amounts in a column on a work sheet and having a letter spacing carriage, a unit on said carriage for controlling various functions of the machine, a register comprising a plurality of axially aligned wheels, and a cycling general operator for running indexed amounts into the wheels of the register; the improvement comprising spring-operated sensing means for ascertaining the clear condition of the register, a pair of normally effective locks each of which is capable of preventing operation of said sensing means, means for releasing one of said locks at a prede-

termined columnar letter space position of the carriage, means for releasing the other of said locks during a machine cycle, and a power-actuated clear sign printing train the action of which is instituted by said sensing means when both of said locks are released and when the sensing means finds the register to be clear.

3. In a credit balance computing machine having a register which is movable to different positions from a normally neutral position for adding and subtracting, a cycling general operator for running indexed amounts into the wheels of the register, a state control means for determining whether the register is to be moved during a cycle from its neutral position into its adding or subtracting position, a spring-urged member associated with said state control means, an interlock between said state control means and said spring-urged member constructed and arranged to prevent operation of said spring-urged member at all times when said state control means has not been moved to determine an adding or subtracting condition of the register, and a sign printing train the operation of which is instituted by said spring-urged member.

4. In a credit balance computing machine having a register which is movable to different positions from a normally neutral position for adding and subtracting, a cycling general operator for running indexed amounts into the wheels of the register, a state control means for determining whether the register is to be moved during a cycle from its neutral position into its adding or subtracting position, sensing means associated with the register for ascertaining a clear condition thereof, an interlock between said state control means and said sensing means constructed and arranged to prevent operation of said sensing means at all times when said state control means has not been moved to determine an adding or subtracting condition of the register, and a clear sign printing train the operation of which is instituted by said sensing means when said sensing means is operated and upon operation finds the register to be clear.

5. In a credit balance computing machine having a register which is movable to different positions from a normally neutral position for adding and subtracting, a cycling general operator for running indexed amounts into the wheels of the register, a state control means for determining whether the register is to be moved during a cycle from its neutral position into its adding or subtracting position, sensing means associated with the register for ascertaining a clear condition thereof, an interlock between said state control means and said sensing means constructed and arranged to prevent operation of said sensing means at all times when said state control means has not been moved to determine a subtracting condition of the register, and a clear sign printing train the operation of which is instituted by said sensing means when said sensing means is allowed to operate and upon operation finds the register to be clear.

6. In a credit balance computing machine having a register which is movable to different positions from a normally neutral position for adding and subtracting, a cycling general operator for running indexed amounts into the wheels of the register, a state control means for determining whether the register is to be moved during a cycle from its neutral position into its adding or subtracting position, sensing means associated

with the register for ascertaining a clear condition thereof, an interlock between said state control means and said sensing means constructed and arranged to prevent operation of said sensing means at all times when said state control means has not been moved to determine an adding condition of the register, and a clear sign printing train the operation of which is instituted by said sensing means when said sensing means is allowed to operate and upon operation finds the register to be clear.

7. In a credit balance computing machine having a register which is movable to different positions from a normally neutral position for adding and subtracting, a cycling general operator for running indexed amounts into the wheels of the register, a fore-and-aft movable slide for determining whether the register is to be moved during a cycle from its neutral position into its adding or subtracting position, spring-operated sensing means associated with the register for ascertaining a clear condition thereof, an interlock between said fore-and-aft movable slide and said sensing means constructed and arranged to prevent operation of said sensing means at all times when said fore-and-aft movable slide has not been moved to determine an adding or subtracting condition of the register, and a clear sign printing train the operation of which is instituted by said sensing means when said sensing means is allowed to operate and upon operation finds the register to be clear.

8. In a credit balance computing machine having a register which is movable to different positions from a normally neutral position for adding and subtracting, a cycling general operator for running indexed amounts into the wheels of the register, a state control means for determining whether the register is to be moved during a cycle from its neutral position into its adding or subtracting position, a spring-urged member associated with said state control means, an interlock between said state control means and said spring-urged member constructed and arranged to prevent operation of said spring-urged member at all times when said state control means has not been moved to determine an adding or subtracting condition of the register, a sign printing train the operation of which is instituted by said spring-urged member, and means associated with said cycling general operator for delaying the operation of said spring-urged member until the last half of the cycle.

9. In a credit balance computing machine having a register which is movable to different positions from a normally neutral position for adding and subtracting, a cycling general operator for running indexed amounts into the wheels of the register, a state control means for determining whether the register is to be moved during a cycle from its neutral position into its adding or subtracting position, sensing means associated with the register for ascertaining a clear condition thereof, an interlock between said state control means and said sensing means constructed and arranged to prevent operation of said sensing means at all times when said state control means has not been moved to determine an adding or subtracting condition of the register, a clear sign printing train the operation of which is instituted by said sensing means when said sensing means is allowed to operate and upon operation finds the register to be clear, and means associated with said cycling general oper-

ator for delaying the operation of said sensing means until the last half of the cycle.

10. In a credit balance computing machine adapted for printing amounts in a column on a work sheet and having a letter spacing carriage, a register which is movable to different positions from a normally neutral position for adding and subtracting, a unit on said carriage for controlling various functions of the machine, and a cycling general operator for running indexed amounts into the wheels of the register; the improvement comprising a state control means for determining whether the register is to be moved during a cycle from its neutral position into its adding or subtracting position, a spring-urged member associated with said state control means, an interlock between said state control means and said spring-urged member constructed and arranged to prevent operation of said spring-urged member at all times when said state control means has not been moved to determine an adding or subtracting condition of the register, a normally effective lock for preventing operation of said spring-urged member, said lock being releasable at only one predetermined letter space position in a column, and a sign printing train the operation of which is instituted by said spring-urged member.

11. In a credit balance computing machine adapted for printing amounts in a column on a work sheet and having a letter spacing carriage, a register which is movable to different positions from a normally neutral position for adding and subtracting, a unit on said carriage for controlling various functions of the machine, and a cycling general operator for running indexed amounts into the register; the improvement comprising a state control means for determining whether a register is to be moved during a cycle from its neutral position into its adding or subtracting position, sensing means associated with the register for ascertaining the clear condition thereof, an interlock between said state control means and said sensing means constructed and arranged to prevent operation of said sensing means at all times when said state control means has not been moved to determine an adding or subtracting condition of the register, a normally effective lock for preventing operation of said sensing means, said lock being releasable at only one predetermined letter space position in a column, and a clear sign printing train the operation of which is instituted by said sensing means when said sensing means is allowed to operate and upon operation finds the register to be clear.

12. In a credit balance computing machine adapted for printing amounts in a column on a work sheet and having a letter spacing carriage, a register which is movable to different positions from a normally neutral position for adding and subtracting, a column unit on said carriage for controlling various functions of the machine, and a cycling general operator for running indexed amounts into the register; the improvement comprising a fore-and-aft movable slide for determining whether a register is to be moved during a cycle from its neutral position into its adding or subtracting position, spring-operated sensing means associated with the register for ascertaining the clear condition thereof, an interlock between said fore-and-aft movable slide and said sensing means constructed and arranged to prevent operation of said sensing means at all times when said fore-and-aft movable slide has not been moved to determine an adding or subtract-

ing condition of the register, a normally effective column unit controlled lock for preventing operation of said sensing means, said lock being releasable at only one predetermined letter space position in a column, a general operator controlled lock constructed and arranged to allow operation of said spring-operated sensing means only after a cycle has progressed beyond the half-way mark, and a sign printing train the operation of which is instituted by said sensing means when said sensing means is allowed to operate and upon operation finds the register to be clear. 10
